HYDROCARBON CONVERSION PROCESS

Roland B. Day and Elmer R. Kanhofer, Chicago,
Ill., assignors to Universal Oil Products Com-
pany, Chicago, Ill., a corporation of Delaware

Application March 31, 1941, Serial No. 386,113

4 Claims. (Cl. 196—52)

This invention relates to a process for the conversion of relatively high boiling hydrocarbon oil into lighter and more valuable hydrocarbons, and more particularly it is concerned with a process wherein said relatively high boiling hydrocarbon oil is cracked by a combination of thermal and catalytic steps to produce a high antiknock gasoline.

In the process of our invention the products from a catalytic cracking step are fractionated to separate gasoline boiling range hydrocarbons, a light reflux condensate and a heavy reflux condensate. The heavy reflux condensate separated by fractionation of the products from catalytic cracking is commingled with a light reflux condensate fractionated from the products of a thermal cracking process and the mixture formed into a combined feed for said thermal cracking step. The heavy reflux condensate separated by fractionation of the products from the thermal cracking step is commingled with the light reflux condensate separated from the products of the catalytic cracking step and with the charging stock to form the combined feed for the catalytic cracking step. The heavy reflux condensate separated from the products of the catalytic cracking step would when returned to said catalytic cracking step result in the formation of considerable quantities of carbon on the catalyst and consequently result in an increase in cost of the regenerating of the catalyst. In the process of our invention, this fraction containing these coke-forming materials is directed to a thermal cracking step and either cracked or removed as a non-volatile liquid residue from the products of said thermal cracking step.

In one specific embodiment our invention comprises a process for the production of gasoline by a combination of thermal and catalytic cracking steps wherein a relatively high boiling hydrocarbon oil, such as a gas oil, and recycle streams formed as hereinafter set forth are cracked in the presence of a siliceous cracking catalyst with the formation of substantial quantities of gasoline, the products from said catalytic cracking step fractionated to separate said gasoline, light intermediate conversion products and heavy intermediate conversion products, commingling said heavy intermediate conversion products with the light intermediate conversion products separated from the products of the thermal cracking step of the process and subjecting said mixture to said thermal cracking step to thermal cracking conditions to form substantial quantities of gasoline, subjecting the products from said thermal cracking step to a vaporizing and separating step to remove a non-volatile liquid residue, fractionating the vaporous fraction to separate the gasoline and normally gaseous products, light intermediate conversion

products, and heavy intermediate conversion products, and commingling said heavy intermediate conversion products with the light intermediate conversion products separated from the aforesaid catalytic cracking step and with the raw oil charging stock to form the combined feed for the catalytic cracking step for treatment as hereinbefore set forth.

The accompanying diagrammatic drawing illustrates in conventional side elevation one specific form of apparatus which may accomplish the objects of the invention.

Referring to the drawing a relatively high boiling hydrocarbon oil is supplied through line 1, valve 2 to pump 3 which discharges into line 4 wherein said charging stock is commingled with a recycle stream formed by commingling the heavy intermediate conversion products formed in the thermal cracking step of the system and the light intermediate conversion products formed in the catalytic cracking step of the system. This combined feed is directed from line 4 to heating coil 5 so disposed as to receive heat from furnace 6. The oil in passing through heating coil 5 is heated to a temperature within the approximate limits of 900-1100° F. and at a pressure of the order of 50-500 pounds per square inch. This heated oil is directed from coil 5 to line 7 from which, after passing through valve 8, it is supplied to one of a plurality of reaction chambers having disposed therein a cracking catalyst of the type, such as silica-alumina, composites of silica and alumina with other components, such as hydrated thoria or hydrated zirconia or blends of hydrated silica with hydrated zirconia or hydrated thoria. Although the process is not limited to any number of reactors, for the sake of simplicity, two are shown in the drawing, one of which, in the process being described, is used for the conversion of hydrocarbons, while the catalyst in the other is being subjected to a regeneration process. The hydrated oil in line 7 is then directed to line 8 from which it passes through either valve 9 or valve 10, being supplied to reactor A or B as the case may be. The reactors A and B may be of the adiabatic type, that is, the heat absorbed in the conversion process being obtained from the reactants themselves, or if desired, heat exchange types of reactors may be used. Adiabatic reactors have the advantage of simplicity of construction, but in some cases where it is desired to maintain more nearly isothermal conditions, heat may be supplied by means of combustion gases, molten salts, or the like. In the adiabatic reactors, the catalyst may be disposed in relatively wide beds, while in the heat exchange type, it is often disposed in a plurality of tubes, or if desired, in beds with heat distributing members for supplying the heat needed for the reactions. The temperature at the

outlet of the reaction chamber is within the range of 800-1100° F. with pressures varying from substantially atmospheric to 100 or more pounds per square inch. It is also within the scope of this invention to use, if desired, certain diluents, such as steam, in the catalytic cracking zone. The conversion products leave either reactor A or B as the case may be, and are directed into line 11 and after passing through valves 12 or 13 are supplied to line 14 discharging into fractionating column 15. The conversion products are preferably cooled before being supplied to the fractionating column which may be done by quenching them with reflux condensate obtained from said fractionating column. Methods for accomplishing this quenching are well known in the art.

Fractionating column 15 separates as an overhead product gasoline boiling range hydrocarbons and normally gaseous products, this mixture being removed by way of line 16 controlled by valve 17 from which it is supplied to cooler and condenser 18. The mixture of liquid, together with undissolved and uncondensed gases, is removed from condenser 18 by way of line 19 and after passing through valve 20 is directed to receiver and separator 21. The gases collected in receiver 21 are removed by way of line 22 and after passing through valve 23 are removed from the system. The olefinic constituents of said gases may be polymerized if desired to form gasoline boiling range hydrocarbons, or if desired, the isoparaffinic constituents of said gases may be alkylated with the olefins to form a saturated motor fuel. The liquid collected in receiver 21 is removed by way of line 24, valve 25 and constitutes a product of the process. It may be stabilized by well known methods to form motor fuel of the desired volatility. A light reflux condensate is removed as a side cut from fractionating column 15 by way of line 26 and after passing through valve 27 is supplied to pump 28 which discharges into line 29. This light reflux condensate is commingled in line 30 with the heavy reflux condensate formed in the thermal cracking step of the system and the mixture directed to line 4 wherein it is commingled with the charging stock for the process to form the combined feed for the catalytic cracking step.

The heavy reflux condensate separated from fractionating column 15 is removed by way of line 31 and after passing through valve 32 is supplied to pump 33 which discharges into line 34 controlled by valve 35. After passing through valve 35 this heavy reflux condensate is commingled with the light reflux condensate formed in the thermal cracking step of the process and the mixture directed to heating coil 36 so disposed as to receive heat from furnace 37. The products from heating coil 36 are at a temperature within the approximate limits of 875-1000° F. and a pressure which may vary from about 50 to about 400 pounds per square inch and are directed to line 38 from which, after passing through valve 39, they are supplied to reaction chamber 40. The function of this insulated reaction chamber is a continuance of the cracking reaction begun in coil 36. The reaction products from chamber 40 are directed to line 41 and after passing through valve 42 are supplied to flash chamber 43 which operates at a pressure lower than that of the communicating reaction chamber and which may be of the order of 25-200 pounds per square inch. Owing to the reduction of pressure in flash chamber 43 addi-

tional vaporization of the hydrocarbons takes place, the mixture of vapors formed in the cracking operation and that due to the flashing operation being removed from said flash chamber by way of line 44 from which, after passing through valve 45 and after quenching, it is supplied to fractionating column 46. The non-vaporous liquid residue separated from the vapors in the flash chamber is removed from the system by way of line 47 controlled by valve 48.

Gasoline boiling range hydrocarbons and normally gaseous products are separated as an overhead from column 46 by way of line 49 and after passing through valve 50 are supplied to cooler and condenser 51 wherein the normally liquid products are condensed. The mixture of liquid, together with undissolved and uncondensed gases, is directed from cooler and condenser 51 to line 52 controlled by valve 53 from which it is supplied to receiver and separator 54. The gases separated in receiver 54 are removed from the system by way of line 55 controlled by valve 56. The olefinic constituents of said gases may be polymerized to form a motor fuel, or if desired, the isoparaffinic constituents thereof may be alkylated by the olefins to form a saturated motor fuel. The liquid collected in receiver 54 is removed by way of line 57 controlled by valve 58 and constitutes a product of the process and may be stabilized to form a motor fuel of the desired volatility.

The light reflux condensate is removed as a side cut from column 46 by way of line 59 and after passing through valve 60 is supplied to pump 61, discharging through line 62, valve 63 into line 34 wherein said light reflux condensate is commingled with the heavy reflux condensate formed in the catalytic cracking step and the mixture is subjected to thermal cracking as hereinbefore set forth. The heavy reflux condensate, freed from carbon-forming materials by the flashing operation conducted in chamber 43 as hereinbefore set forth, is removed from column 46 by way of line 64 and after passing through valve 65 is supplied to pump 66 which discharges into line 30 wherein said heavy reflux condensate is commingled with the light reflux condensate formed in the catalytic cracking step and the mixture directed to line 4 wherein it is commingled with the charging stock and the mixture subjected to catalytic cracking as hereinbefore set forth.

An example of one specific operation of the process as it may be accomplished in an apparatus such as illustrated and above described is approximately as follows: Charging oil comprising a 34.5 A. P. I. gravity Pennsylvania gas oil is commingled with light intermediate conversion products from the catalytic cracking step and heavy intermediate conversion products from the thermal cracking step, vaporized and heated to a temperature of about 960° F. These heated vapors pass in contact with a mass of synthetically prepared silica-alumina catalyst at a pressure of 30 pounds per square inch and for a time of contact sufficient to form about 30 volume per cent of gasoline per pass. The catalytic conversion products are fractionated to separate vapors of 400° F. end point from the higher boiling and insufficiently converted hydrocarbons. The gasoline is separated from the normally gaseous products and collected as a product of the process.

The insufficiently converted hydrocarbons from the thermal cracking step are fractionated into

light insufficiently converted hydrocarbons and heavy insufficiently converted hydrocarbons. The light insufficiently converted hydrocarbons from the thermal cracking step are commingled with the heavy insufficiently converted products from the catalytic cracking step and the mixture subjected to thermal cracking at a temperature of 920° F. and a pressure of 300 pounds per square inch at the outlet of the heating coil, employing a reaction chamber and utilizing such a time of reaction that approximately 20% of the charge of the thermal cracking step is cracked per pass. The thermally cracked products are then subjected to a flashing operation to separate non-volatile liquid residue from the vaporous reaction products. The products from the thermal cracking step are then fractionated to separate gasoline, normally gaseous products, light intermediate conversion products and heavy intermediate conversion products. The heavy intermediate conversion products from the thermal cracking step are then blended with the light intermediate conversion products from the catalytic cracking step and with a gas oil charging stock to form the combined feed for the catalytic cracking step for treatment as hereinbefore set forth.

For an operation employing conditions as above mentioned, one may obtain approximately 45.2% of 400° end point catalytically cracked gasoline having an octane number of 79.5, approximately 22.8% of 400° end point thermally cracked gasoline of 69.5 octane number and 20.0% liquid residue of 8.5° A. P. I. gravity, the balance being principally carbon and gaseous products.

We claim as our invention:

1. A process for the production of gasoline which comprises subjecting a combined feed formed as hereinafter set forth to catalytic cracking, fractionating from the products of said catalytic cracking step gasoline, light intermediate conversion products, and heavy intermediate conversion products, commingling said heavy intermediate conversion products with light intermediate conversion products formed in a thermal cracking step as hereinafter set forth and subjecting the mixture to thermal cracking to form substantial quantities of gasoline, separating the products of said thermal cracking step into a non-vaporous liquid residue and a vaporous fraction, fractionating said vaporous fraction to separate gasoline, light intermediate conversion products and heavy intermediate conversion products and commingling the heavy intermediate conversion products from the thermal cracking step with the light intermediate conversion products from the catalytic cracking step and with a relatively high boiling hydrocarbon oil charging stock to form the combined feed for the catalytic cracking step.

2. A process for the production of a gasoline which comprises subjecting a combined feed formed as hereinafter set forth to the action of a siliceous cracking catalyst at a temperature within the approximate limits of 800-1100° F. and a pressure of from substantially atmospheric to approximately 100 pounds per square inch and for a time of contact adequate to the formation of substantial quantities of gasoline, fractionating from the products of said catalytic cracking step gasoline, light intermediate conversion products and heavy intermediate conversion products, commingling said heavy intermediate

diate conversion products with light intermediate conversion products formed in a thermal cracking step as hereinafter set forth and subjecting the mixture to a temperature within the approxi-

- 5 mate limits of 875-1000° F. and at a pressure of from about 50 to about 400 pounds per square inch and for a sufficient period of time to form substantial quantities of gasoline, separating the products of said thermal cracking step into a
10 non-vaporous liquid residue and a vaporous fraction, fractionating said vaporous fraction to separate gasoline and normally gaseous products, light intermediate conversion products and heavy intermediate conversion products, and commingling the heavy intermediate conversion products from the thermal cracking with the light intermediate conversion products from the catalytic cracking step and with a relatively high boiling hydrocarbon oil charging stock to form the combined feed for the catalytic cracking step.
15 3. A process for the production of gasoline by a combination of a thermal cracking step and a catalytic cracking step which comprises subjecting a combined feed formed as hereinafter
20 set forth to catalytic cracking, fractionating the products of said catalytic cracking step in commingled state with a raw oil charging stock to separate gasoline and normally gaseous products, a light reflux condensate and a heavy reflux condensate, commingling said heavy reflux condensate with a light reflux condensate separated from the products of the thermal cracking step and subjecting said mixture to thermal cracking, separating the products of said thermal cracking
25 step into a non-vaporous liquid residue and a vaporous fraction, fractionating said vaporous fraction to separate gasoline and normally gaseous products, a light reflux condensate and a heavy reflux condensate, and commingling the
30 heavy reflux condensate from the thermal cracking step with the light reflux condensate from the aforesaid catalytic cracking step to form the combined feed for the aforesaid catalytic cracking step.
35 4. A process for the production of gasoline which comprises maintaining a catalytic cracking step and a thermal cracking step, subjecting conversion products from the thermal cracking step to a vaporizing and separating step to separate a non-volatile liquid residue from the remaining vapors, fractionating said remaining vapors to separate gasoline, normally gaseous products, light intermediate conversion products and heavy intermediate conversion products,
40 fractionating the products from the catalytic cracking step to separate gasoline, normally gaseous products, light intermediate conversion products, and heavy intermediate conversion products, commingling the light intermediate conversion products from the thermal cracking step with the heavy intermediate conversion products from the catalytic cracking step to form the combined feed for the thermal cracking step and commingling the heavy intermediate conversion products from the thermal cracking step with the light intermediate conversion products from the catalytic cracking step and a charging stock comprising fractions boiling above the range of gasoline and subjecting this mixture
45 to the aforesaid catalytic cracking step.
